UNITED STATES PATENT OFFICE.

HARRY S. FREEMAN, OF DETROIT, AND FREDRICK ZENKER, OF HIGHLAND PARK, MICHIGAN, ASSIGNORS TO SQUARE D COMPANY, OF DETROIT, MICHIGAN, A CORPORATION OF MICHIGAN.

ELECTRIC SWITCH.

1,400,279.

Specification of Letters Patent. Patented Dec. 13, 1921.

Application filed October 24, 1917. Serial No. 198,256.

To all whom it may concern:

Be it known that we, HARRY S. FREEMAN, a citizen of the United States, residing at Detroit, in the county of Wayne and State of Michigan, and FREDRICK ZENKER, a subject of the Emperor of Germany, residing at Highland Park, in the county of Wayne and State of Michigan, have invented certain new and useful Improvements in Electric Switches, of which the following is a specification.

This invention relates to electric switches and with regard to certain more specific features thereof to combined fuse-holding and circuit-operating devices.

It is one of the objects of this invention to provide a simple and durable fuse-holding switch of the nature above specified.

Another object of the invention lies in the provision of inexpensive and otherwise improved contacts and fuse-retaining means which shall be reliably efficient in operation and which may be assembled and disassembled by relatively unskilled workmen.

Another object of the invention resides in the provision of simplified and otherwise improved means for pivotally associating certain of said contacts.

Another object of our invention is to provide a fuse-holding switch which may be readily assembled from parts, the majority of which are of standard construction. As such parts may be produced by the usual machinery, they are cheaper than special parts which have heretofore been used, and in addition the current carrying capacities of these standard parts and their proper construction is well known. A complete line of our improved type of switches may be built from a comparatively small number of standard pieces along with a few special parts.

Another object of our invention is to reduce the size of fuse-holding switches as much as possible. Our switch need be no longer than the fuse it carries and no wider than the diameter of the fuse.

Another object of our invention is to improve fuse-holding switches by eliminating all unnecessary resistances, which may be done by shortening the current paths to a minimum.

Other objects will be in part obvious and in part pointed out hereinafter.

While our invention may take form in many different embodiments, we will describe in detail one of these embodiments showing a construction having one convenient arrangement of parts and combination of elements for building up a switch. The scope of our invention is, however, to be limited solely by the claims and the prior state of the art.

In the accompanying drawings wherein is shown one of various possible embodiments of the invention.

Figure 1 is a view in side elevation of an electric switch comprising features of the invention;

Fig. 2 is a front elevational view of Fig. 1;

Fig. 3 is a view in section taken on line 3-3 of Fig. 2;

Fig. 4 is a sectional view taken on the line 3-3 of Fig. 2 but with the fuse detached;

Fig. 5 is a view in section taken on the line 5-5 of Fig. 2.

Referring now more particularly to the drawing wherein similar reference characters indicate similar parts throughout the several views, there is indicated at 1 a base of insulating material upon which there are fixed spaced apart clip contacts 2 and 3. Substantially surrounding the clip contact 2 there is a compression member or clip 4 for purposes which will hereinafter be set forth.

The clip contact 2 is in the form shown made from a standard knife blade clip contact and comprises a flat comparatively wide base portion 10 and oppositely disposed upwardly extending walls 11, which are bowed inwardly as indicated at 12 to form spaced compression jaws 13. The compression member 4 is also provided with a relatively wide base portion 14 and upwardly extending side walls 15 bowed inwardly to provide substantially parallel compression walls 16, each of which carries a riveted compression stud 17 the inner end of which is of frusto-conical shape and is adapted to seat within a cup-shaped aperture 18 in each pivotal stud 19. The pivot studs are loosely mounted in apertures 20 in the jaws or walls 13 of the clip contact 2 and each pivot stud is provided with a suitable shoulder to limit the projec-

tion of the stud inwardly from the walls 13. This projection should substantially correspond with the thickness of the jaws or walls of another clip contact which will hereafter be described. Upon reference to Figs. 3 and 4 of the drawing it will be obvious that the compression member 4 substantially surrounds the clip contact 2 and that a screw 25 passed through from the opposite side of the base 1 secures the compression member 4, the clip contact 2 and a connector 5 together and to the base 1. These parts are further secured against possible angular displacement by means of a screw 26 passed through from the opposite side wall of the base, and binding the connector strip 5 and a terminal 6 together and to the base 1. This provides a two-point attachment for the connector strip 5, which is rectangular in shape and the side walls of which are adapted to engage with the side walls 11 of the clip contact 2 and prevent angular movement of the latter. Angular displacement of the compression member is also restricted by the side walls 11 of the clip contact in turn resting proximate the side walls 15 of the compression member. By the construction just described the parts are all firmly secured in electrical communication and also are firmly held against displacement relatively to the base 1. The screw 25 serves as a binding post and to this end it is provided with a nut 27.

It will be noted that a lower connecting strip 5' is bent upwardly as at 5^a to provide a stop for a clip 42 and a fuse blade 54, as shown in Fig. 5. The contact 3 is in the form shown a standard clip contact of the type used for receiving a knife blade and is formed with a flat relatively wide base portion 28 and upstanding side walls 29 each of which is bowed inwardly and downwardly as indicated at 30. The downward projections 31 serve as contact jaws and preferably are spaced to receive another clip contact with suitable contacting compression. The base 28 of the clip contact 3 is mounted directly on the insulating base 1 and is secured thereto by a screw 33 which is passed through from the opposite side of the base and tapped into connector strip 5'. This connector strip is also secured by a screw 34, corresponding to the screw 25. The rectangular side walls of the connector strip 5' prevent angular displacement of the clip contact 3, and the screw 34 serves as a binding post for another terminal 6.

The structure so far described is intended as a substitute generally for the base block and contacts of the well-known pivotal knife-blade switch. The structure of the present invention intended as a substitute for the pivotal knife-blade will now be described.

At 40 there is indicated a carrier or what 65 may be termed a bridging element or bridge, in that one of its functions is to span the spaced apart clip contacts 41 and 42 and by pivotal movement of these contacts, as will hereinafter be described, to mechanically 70 connect the base contacts 2 and 3. This bridging element is preferably of insulation but it may be of metal, possibly of electrical conductivity provided the contacts 41 and 42 are suitably insulated. The clip contacts of 75 the bridging element are secured thereto by means of screws 43 passed through from the opposite side of the bridging element and tapped into square nuts 44. Each of the clip contacts 41 and 42 is of the usual type 80 and comprises pairs of spaced parallel compression jaws 45, and 45^a, respectively, the former pair being apertured to receive the inwardly projecting portion of the pivoted studs 19. By slightly compressing the jaws 85 45 this assembly can be made after which the bridging element may be pivotally moved by means of a handle 50 to cause engagement and disengagement of the clip contact 42 with the clip contact 3 of the base. 90

A fuse 51 is provided of the inclosed type preferably of cartridge form having a shell 52 of fiber or some suitable insulating material, and caps 53 of metal and flattened knife-blade terminals 54 projecting outwardly from the shell or cartridge to a suitable extent for good electrical and retaining connection with the clips 41 and 42. The fuse 51 may be detachably attached to the bridging element 40 by forcing the knife-blade terminals between the opposing walls 45 and 45^a of the clip contacts 41 and 42, respectively. These walls are so spaced as to exert substantial pressure on the flat knife-blade terminals when the fuse is attached in order that there will be good, electrical and retaining connection. The insertion of the fuse terminals between the walls forces them out to cause their outer surfaces to engage with the inner surfaces of the jaws 13 and 31 of the contacts 2 and 3, respectively, with good electrical communication and suitable friction. 100 105 110

The upwardly bent part 5^a of the connector strip 5 co-operates with the clip 42 115 when in the closed position to form a stop. It, therefore, prevents the wedging apart of projections 31 by the inwardly bowed portions 42. The prevention of such wedging is important as otherwise the projections 31 120 might be forced apart and a poor contact with excessive heating result. This is clearly shown in Fig. 5.

When the switch is closed rapidly, the carrier is brought to an abrupt stop. As the 125 fuse, however, is merely retained by the friction of the clip 42, it tends to continue in its movement. The stop 5^a, however, limits this

motion and prevents dislodging the blade from the clip. The same element, therefore, is used to act as a stop for the carrier and for the fuse.

5 The compression member 4 through its compression walls and the stud 17 bearing against the pivot studs 19 increase the effectiveness of the contact between the clips 2 and 41, yet said member is sufficiently 10 yieldable to allow quick and convenient disassembly of the pivoted structure. In operation the fuse may be attached or detached without disassembling the pivot and the jaws or walls of the clip contacts are 15 so spaced and arranged as to have their maximum contact and retaining efficiency when the fuse is attached and the switch is closed. Obviously the closing of the switch completes a circuit from one of the 20 terminals 8 to the other through the fuse 51, the insulating properties of the base 1 and the bridging element 40 preventing any other path of electrical communication.

As many changes could be made in the 25 above construction and as many apparently widely different embodiments of the invention could be made without departing from the scope thereof, it is intended that all matter set forth in the foregoing description 30 or shown in the accompanying drawings shall be interpreted as illustrative and not in a limiting sense.

What is claimed is:—

1. In a switch, in combination, a bridge, 35 clip contacts mounted thereon having open parallel jaws, a cartridge fuse having flattened terminals that are held in frictional engagement with said contacts by passing the flattened terminals between the said open 40 parallel jaws, a base and contacts fixed thereon, comprising jaws adapted to embrace the jaws of the clip contacts of said bridge with the interposed flattened terminal of the fuse.

45 2. In a switch, in combination, a bridge, clip contacts mounted thereon having spaced parallel and resilient jaws, a cartridge fuse having flattened terminals connectible to said contacts by frictionally engaging the 50 flattened terminals with said parallel jaws, a base, contacts fixed thereon comprising spaced and parallel jaws adapted to receive the clip contacts of said bridge with said flat fuse terminals, and means for pivotally associating one of the bridge contacts with one 55 of the base contacts.

3. In a switch, in combination, a base, a 60 clip contact mounted thereon having apertured jaws, a bridge having a clip contact comprising spaced and apertured jaws, and compression members bearing thereon, means comprising spaced and alined pivot studs for severally and pivotally connecting together said clip contacts through their

apertured jaws, a third clip contact mounted 65 on said base and having jaws, a fourth clip contact secured to said bridge and having spaced walls, and an inclosed fuse element having means for passing between the opposed ends of said pivot studs and for engaging said third and fourth contacts between the spaced walls thereof.

4. In a switch, a base, a pair of spaced apart contacts mounted thereon, a bridging element having a pair of contacts spaced apart and relatively insulated, a cartridge fuse having flat knife-blade terminals, the base contacts having jaws for receiving within them the bridging element contacts, and the latter said contacts comprising jaws 75 for detachably receiving within them the fuse terminals, and means comprising alined and spaced apart pivot studs and a compression device bearing against said studs on opposite sides of one of said base 80 contacts for pivotally securing one of the bridging element contacts to a co-operating base contact.

5. In a switch, in combination, a base having mounted thereon a contact having parallel spaced apart jaws and provided with outwardly bowed portions, a carrier having mounted thereon a second contact having parallel spaced apart jaws and provided with outwardly bowed portions, said last mentioned jaws being receivable within the first mentioned jaws, and means for limiting the motion of the second jaws within the first jaws and preventing the separation of the first set by the bowed portions of the 100 second set; substantially as described.

6. In an electric switch, in combination, a base; a carrier, two contacts on each spaced apart to form pairs, one contact of each pair being receivable within the other contact of the corresponding pair, one of the receiving contacts being resilient to closely press the other contact of the pair, and means comprising a spring adjacent the other receiving contact to press that contact toward the 105 other contact of the second pair; substantially as described.

7. In an electric switch, the combination with an inclosed fuse element having end caps that are severally provided with integrally formed flat terminals, an insulating carrier, contact members mounted on said carrier and having parallel spaced and resilient jaw-members to frictionally engage on their inner faces said flat terminals of 115 the fuse element, of a base member comprising contact members having spaced resilient jaw-members that are adapted to receive in frictional engagement the jaw-members of the carrier contact members 120 with the interposed flat terminals of said fuse element, and means for pivotally securing the said carrier to said base member.

- 4.
8. In an electric switch, the combination therewith the jaw-portions of the other with two co-operating contact members, each contact member, and a flat conducting terminal interposed between, and frictionally having flat spaced resilient jaw-portions 10. the opposed surfaces of which are parallel engaging with, the opposing surfaces of the and the jaw-portions of one contact member jaw-portions of said second contact member. being adapted to receive between its opposing surfaces and in sliding engagement

HARRY S. FREEMAN.
FREDRICK ZENKER.
